UNITED STATES PATENT OFFICE.

ALEXANDER HOGELAND, OF LOUISVILLE, KENTUCKY.

SHIP-CANAL.

SPECIFICATION forming part of Letters Patent No. 630,457, dated August 8, 1899.

Application filed March 3, 1899. Serial No. 707,639. (No model.)

To all whom it may concern:

Be it known that I, ALEXANDER HOGELAND, a citizen of the United States, residing at Louisville, in the county of Jefferson and State of Kentucky, have invented a new and useful Improvement in Ship-Canals, of which the following is a specification.

My invention relates to an improved construction of ship-canal, and has for its object to provide a canal which is practically above ground for the principal part of its course from one ocean, river, or lake to another, as the case may be, and thereby obviates the laborious and expensive excavating, dredging, washouts, and other difficulties incidental to an ordinary dug canal, such as the attempted Panama and proposed Nicaraguan canals.

The invention consists in features of novelty, as hereinafter described and claimed, reference being had to the accompanying drawings, forming part of this specification, whereon—

Figure 1 is a cross-section through my improved ship-canal; Fig. 2, a top plan thereof broken away; Fig. 3, a cross-section, to enlarged scale, through one of the side walls of the canal on line 3 3 in Fig. 6, showing one of the buttresses forming part of my invention in side elevation; Fig. 4, a top plan of the same; Fig. 5, an outer end view to enlarged scale of the lower part of the buttress and its supporting-beam as seen on line 5 5 in Fig. 3; Fig. 6, an outside elevation of the side wall, broken away, of the canal seen in Fig. 3, omitting the longitudinal trusses for the side wall between consecutive buttresses; and Fig. 7, a horizontal section on line 7 7 in Fig. 3, showing one of the said trusses. Fig. 8 is a view corresponding to Fig. 3, showing the application of my invention to a sea, river, harbor, or dock wall; and Fig. 9, a bird's-eye view of an extended length of the canal, showing a terminal portion in the foreground, which is constructed in the ordinary well-known manner and provided with the usual locking system for admitting and raising ships from the ocean or other navigable water to the level of my improved elevated portion of the canal.

Like letters and numerals of reference denote like parts in all the figures.

A represents a portion of my improved

aqueduct ship-canal, which is built practically above ground for any desired length. The side walls 1 and bottom 2 of the canal 55 are composed of iron or steel plates of suitable dimensions having, preferably, butt-joints, which are covered externally by and securely riveted to plates and strips, as hereinafter more particularly specified, the whole 60 forming a strong and thoroughly water-tight trough or channel throughout the entire length of the canal A. The side walls 1 preferably slope outward from the bottom 2 to the top of the said walls. The entire channel thus constructed is supported on I-beams or other suitably-shaped girders B, which are arranged transversely to the channel 1 2 at suitable distances apart. Each beam B is integral or in one continuous length and horizontal, the bottom 2 of the channel bearing directly on the top of the beams B, which extend for a suitable distance beyond the side walls 1 of the channel and are embedded in a preferably concrete foundation C of suitable depth and area for supporting the entire weight of the canal A, or, in lieu of concrete, rubble, masonry, brick, or other suitable material or combination thereof may be used for the foundation C.

To each extended end portion of each beam B beyond the corresponding side wall 1 of the channel 1 2 is fixed a vertically-arranged and preferably triangular-shaped buttress or frame D, which is preferably composed of 75 angles and T's or other sections of iron or steel suitably arranged and firmly riveted together, the height of the buttress D preferably corresponding to the vertical depth of the channel 1 2, as shown.

One leg 3 of each buttress D bears against the outside of the plates composing the side walls 1 of the channel 1 2 thereat for its entire inclined depth and serves as a cover-plate to the corresponding butt-joints of the 80 said plates, to which the leg 3 is securely riveted.

The base 4 of each buttress D is riveted for its entire length to the corresponding extended end portion of the supporting-beam B. 85

Between consecutive buttresses D throughout the entire length of the canal A are arranged vertically or following the inclination of the side wall 1 two or more I-beams or other

suitably-shaped girders 5, which bear against the outside of the plates composing the side wall 1 of the channel 12 thereat and serve as cover-plates to the corresponding butt-joints 5 of the said plates, to which the beams 5 are securely riveted. Between the beams 5 and between the latter and the adjacent buttresses D, respectively, are arranged horizontally at suitable distances apart T-irons 6, which serve as cover-plates to the horizontal butt-joints of the plates composing the side wall 1 thereat, to which the T-irons 6 are securely riveted.

Straddling and riveted to the beams 5 in the horizontal plane of each row of T-irons 6 is an angle or other suitably-shaped bar 7, which is fixed at its ends to the corresponding buttresses D and to the plates thereof of the side wall 1, the bar 7 being connected to its corresponding T-irons 6 by bars 8, arranged zigzag, (or latticewise,) as shown in Fig. 7, the whole forming a series of horizontal trusses E for stiffening the side wall 1 between the buttresses D, and thereby enabling the side wall 1 to withstand the pressure of water in the canal A.

By the above construction the channel 12 being made of plating practically in one piece throughout and resting at the bottom 2 directly on the foundation-beams B and fixed at its side walls 1 to the buttresses D, which are also fixed to the said beams B, combined with the horizontal trusses E, which are fixed to the buttresses D and to the side walls 1, the channel 12 of the canal A is firmly held in an iron cradle for its entire length.

If desired, the longitudinal trusses E between the buttresses D may be dispensed with and the necessary stiffness imparted to the side walls 1 by increasing the number of but-

tresses D and placing them closer to each other; but by using the trusses E the distance between the buttresses D can be increased and economy in construction thereby gained.

What I claim as my invention, and desire 45 to secure by Letters Patent, is—

1. An aqueduct-canal having an iron or steel plate channel or trough bearing at the bottom on horizontal beams or girders arranged transversely beneath the channel and 50 respectively integral, the said beams extending beyond the side walls of the channel, and each beam having two opposite buttresses fixed at the base thereto, and at their opposite faces to the side walls respectively of the 55 channel, substantially as described.

2. An aqueduct-canal having an iron or steel plate channel or trough bearing at the bottom on beams arranged transversely beneath the channel, the said beams extending 60 beyond the side walls of the channel and bedded in a foundation of concrete or analogous material, each beam having two opposite buttresses fixed thereto and to the side walls respectively, substantially as described. 65

3. An aqueduct-canal having an iron or steel plate channel or trough bearing at the bottom on beams arranged transversely beneath the channel, the said beams extending beyond the side walls of the channel, and 70 each beam having two opposite buttresses fixed thereto and to the side walls respectively, and trusses fixed along the side walls and having their ends fixed to the buttresses adjacent thereto respectively, substantially 75 as described.

ALEXANDER HOGELAND.
